INCINERATOR

Samuel Letvin, Philadelphia, Pa.

Application November 19, 1945, Serial No. 629,683

7 Claims. (Cl. 110—18)

(Granted under the act of March 3, 1883, as amended April 30, 1928; 370 O. G. 757)

1

This invention relates in general to an incinerator or furnace for burning trash or waste, and more particularly to such a furnace adapted to be installed on board ships or in other locations where the weight of the unit and the space occupied are important considerations.

An object of this invention is to provide a light weight trash burning incinerator or furnace.

Another object is to provide a lightweight trash burning incinerator or furnace having fast-combustion characteristics.

A further object is to provide a trash incinerator or furnace having a minimum amount of refractory lining.

Further objects and advantages of this invention, as well as its construction, arrangement and operation, will be apparent from the following description and claims in connection with the accompanying drawings, in which,

Figure 1 is a side elevation of the furnace of this invention,

Figure 2 is a sectional view taken on the lines 2—2 of Figure 1, and

Figure 3 is a partial front elevation of the furnace shown in Figure 1.

Figure 1 shows an incinerator or furnace, generally designated as 10, supported upon a base 11, and having an ashpit door 12, a feed door 13, and an exhaust outlet or stack 14.

The furnace 10, shown in section in Figure 2, comprises a distorted funnel shaped inner metal shell 15, the small end 16 of which communicates with the stack 14. Around the inner shell 15 and spaced therefrom, so as to form an annular air chamber, is an outer metal shell or casing 17, which may be lagged or coated with suitable insulating material 17a, such as amosite.

A grate 18 is located within the inner shell 15, spaced a sufficient distance above the base 11, so as to provide a suitable ashpit, and secured to the inner shell 15 as at 19. A firebox above the grate comprises refractory side walls 20, which line the inner shell 15 for a distance above the grate 18, the refractory material extending high enough to accommodate the quantity of material being burned when the furnace is operating under normal conditions.

Above the grate 18 are two rows of apertures 22, which extend through the inner shell 15 and the refractory side walls 20, and communicate between the firebox and the annular air chamber. These apertures 22 are preferably directed toward the center of the furnace and are slanted slightly upward in the direction of the ascending hot

2

gases. Optionally the apertures 22 may be installed tangentially so as to impart a swirling or rotary motion to the ascending gases. Another row of apertures 23 is provided in the inner shell 15 above the refractory side wall 20, to communicate between the annular air chamber and the combustion chamber. Air inlets are also provided just above the base 11 as at 24 entering the ashpit below the grate 18.

10 The ashpit door 12 and feed door 13 are comprised of inner plates 25 and an outer plate 26 spaced therefrom, as shown in Figure 1. If induced draft is to be used, the inner plates 25 may contain a plurality of holes as at 27 (Figure 3) for providing additional air for combustion.

In operation, the furnace is fed through the door 13. Air for combustion is supplied by either forced or induced draft. If induced draft is used an exhaust blower (not shown) is installed in the stack 14, and the annular space between the inner shell 15 and outer casing 17 is left open to the atmosphere at the top of the furnace. Air for combustion is drawn down between the outer casing 17 and inner shell 15, cooling the metal parts comprising the firebox and the combustion chamber, and entering the furnace above the grate 18 through the apertures 22. Additional air for combustion is drawn through the inlets 24 and through the grate 18. If holes are provided 15 through the feed door 13 and ashpit door 12 some air also enters at these points.

If forced draft is to be used a blower may be installed, and air ducts may be provided so as to supply air from the blower to the annular space between the inner shell 15 and outer casing 17 at the top of the furnace, with ducts provided if desired communicating with the air inlets 24 below the grate 18. A portion of the air is then forced between the metal shells of 20 the furnace providing cooling of the walls, and the remainder is forced through the grate 18.

By using a furnace having inner and outer metal walls and supplying cooling air between them it is necessary to provide only a small amount of refractory lining within the furnace, thus cutting down materially on the total weight of the unit. Furthermore, due to the supply of preheated air introduced into the combustion space through the apertures above the grate, fast combustion is maintained and a smaller unit can be employed to burn the same amount of material.

A furnace, constructed and operated according to the principles disclosed herein, and having an internal diameter of approximately four feet,

operated efficiently and had the following operating characteristics:

Firing rate (lbs. per hr.)	500
Air flow through furnace (C. F. M.)	3800
Average outlet gas temp., °F.	950
Maximum inner shell temp.	840
Average inner shell temp., °F.	668
Average outer casing temp., °F.	145

5 a feeding door in the inner shell and through the outer casing, a grate within the inner shell, a refractory wall extending a short distance above the grate and lining a portion of the inner shell, the inner shell having a plurality of apertures at spaced intervals in the area of the refractory wall and extending through the inner shell and refractory wall, the inner shell having a plurality of apertures extending through it at spaced intervals in the area above the refractory wall, the apertures being adapted to receive air from the space between the inner shell and outer casing, the incinerator having an air passage at its base for receiving air below the grate.

10 15 4. An incinerator composed of inner and outer metallic shells in spaced relation, the space between the inner and outer shell being open to the atmosphere at its end, a grate located in the inner shell, refractory material lining the interior surface of the inner shell for a portion of its vertical extent above the grate, the inner shell and refractory lining having apertures for the flow of air from the space between the shells, the inner shell also having apertures above the refractory lining.

20 25 5. An incinerator comprising an upright inner metal shell, an outer metal casing around the shell spaced away therefrom and enclosing an air chamber around the shell in contact with the outer surface thereof, the shell being tapered in the upward direction to include an exhaust duct, the air chamber extending upwardly to a position near the exhaust duct and being open to the atmosphere at the top, the inner shell having a plurality of vertically spaced apertures extending from the air chamber into the inner shell.

30 35 6. In an incinerator as defined in claim 5, insulating material covering the exterior surface of the casing.

40 45 7. An incinerator comprising an inner metal shell, an outer casing, the shell and the casing being spaced to provide a passage therebetween which is open to the atmosphere at the top, whereby air delivered against the shell can move downward along the inner shell, and the shell having openings therethrough from the passage to the interior of the shell and below the region where the air is delivered against the shell 50 whereby the air, which has cooled the shell and become warmed, can pass directly into the interior of the shell to assist combustion.
